By G. J. Heinkel.

Attorney

UNITED STATES PATENT OFFICE.

PETER GRABLER, OF ROCKY RIVER, OHIO, ASSIGNOR OF ONE-HALF TO CHARLES E. DAY, OF LAKewood, OHIO.

COPYHOLDER.

Original application filed January 16, 1925, Serial No. 2,720. Divided and this application filed March 11, 1926. Serial No. 94,075.

My invention relates to copy holders generally and to clutch and brake mechanisms adapted to such copy holders particularly.

One of the objects of my invention is a simple and efficient and easily operable and practically noiseless clutch and brake means for operating and locking a rotatable member.

Another object of my invention is a moving means and a brake means, both associated with a movable member and each of which means operates independently of the other and either of which means is operable without operating or interfering with the other means.

Another object of my invention is a brake means, associated with a rotatable member, which locks the rotatable member in any rotative position so that a movable copy support plate, of a copy holder for instance, can be held in any position into which it is moved.

Another object of my invention is a brake means, associated with a movable member, which locks the rotatable member in any rotative position but permits of the rotation of the movable member in one direction so that a movable copy support plate of a copy holder, for instance, can be held in any position into which it is moved and can be moved from that position in one direction.

Another object of my invention is a brake means and a rotating means, both associated with a rotatable member, in which the brake means normally and automatically locks the rotatable member in one direction and in any position into which it is rotated and in which the rotating means is normally and automatically disengaged from the rotatable member but can be rotated in the opposite direction from any of the positions into which the lock means has held the same.

I illustrate my invention in the accompanying drawing which shows one embodiment of my invention and as applied to a copy holder apparatus. I am aware that my invention can have other embodiments and other applications and that changes in the structure of the elements and in the arrange-

ment of the elements can be made within the scope of the appended claims.

In the accompanying drawing:—

Fig. 1 is a front view of a copy holder apparatus embodying the features of my invention and shows, generally, a movable copy support plate and the operating shaft and connecting mechanism to move the plate, and clutch means to either move or to lock the plate in position.

Fig. 2 is a side view of Fig. 1 and shows the elements of Fig. 1 in another plane.

Fig. 3 is a section, on a larger scale, taken on a plane (vertical) indicated by the line 3—3 in Fig. 2, and shows the brake and the rotating mechanism more clearly.

Fig. 4 is a section, taken on a vertical plane indicated by the line 4—4 in Fig. 3, and shows the brake and the rotating mechanisms in another plane.

Fig. 5 is a perspective view of the brake and rotating mechanisms and shows the general association of these mechanisms.

Similar reference characters refer to similar parts throughout the views.

The copy holder selected to illustrate my invention, shown in the accompanying drawing, comprises, generally, the movable copy support plate A, the moving mechanism to move the plate A, and a brake mechanism to lock the moving mechanism, and consequently the plate A against rotation in one direction and in any position into which it may be moved, and operating mechanism to move the moving mechanism, and consequently the plate A in the opposite direction from any locked position.

The plate A is guided in the posts 10 and can slide longitudinally thereon.

The pulley 11, in the present instance having a V groove, is secured to the frame B and is disposed behind the plate A.

The shaft C is journaled in the base D and the pulley 12, complementary to the pulley 11, is secured thereto. The endless belt 13 connects the two pulleys so that the rotation of either one of the pulleys also rotates the other.

The nose 14 is secured to the back of the

plate A and engages the belt 13 so that the rotation of either of the pulleys, and the consequent movement of the belt also moves the plate A.

5 A prominent feature of my invention is a brake mechanism to lock the shaft C into any position it may be rotated into and a rotating mechanism which co-operates with the brake mechanism so that the rotation of the shaft C can be started from any of the locked positions.

10 In the present instance I have shown the brake and the rotating mechanism as operating on a cup-shaped member; it appears 15 obvious that a brake and rotating mechanism may be applied to or associated with other forms.

An operating drum 15, in the present instance formed as a cup and threaded onto 20 the shaft C and against a shoulder, rotates with the shaft C and has the tubular flange 16.

The cover 17 is journaled on the shaft C and closes the open end of the cup 15.

25 The brake mechanism comprises the housing 18 which is disposed on one side of the flange 16 and has the ear 19 which contacts the base D and is held thereon by the screws 20 as seen in Fig. 4.

30 The roller 21 lays loosely or is confined loosely inside of the housing 18.

It is observed that the wall 22 of the housing 18 is angular to or eccentric with the flange 16; it being closer to the flange at the 35 bottom than at the top.

The lever 23 is fulcrumed on the base D and has the nose 24 extending through the wall 22 and into the housing 18 below the bottom of the roller 21.

40 Normally and automatically, the roller 21 falls downwardly due to gravity and one side thereof contacts the outside of the flange 16 while the other side thereof contacts the inside of the wall 22. Since the wall 22 is 45 eccentric with the flange 16, and since the roller 21 normally lays in between the flange 16 and the wall 22, the drum or cup 15, and consequently the shaft C, can not be rotated in the direction of the arrow shown in Fig. 50 4 since the roller 21 wedges in between the flange and the wall as soon as a rotation in that direction is attempted, but the shaft C can be rotated in a direction opposite that shown by the arrow in Fig. 4 since, by such 55 opposite rotation, the roller 21 rolls upwardly and thereby releases itself from the wedging or locking position.

When the outer end 25 of the lever 23 is 60 pressed downwardly, the nose 24 moves upwardly and thereby moves the roller 21 upwardly and out of engagement of the flange 16 and the wall 22 whereupon the brake action of the roller 21 is released or open and the cup or drum 15, and consequently the shaft C, can be rotated in either direction.

With the brake arrangement shown, the shaft C can be rotated in a direction opposite to that shown by the arrow in Fig. 4 and is automatically locked in any rotative position when the brake mechanism is in normal position so that the plate A, through the pulleys 11 and 12 and the belt 13, is securely and automatically held against downward movement as long as the brake mechanism remains in normal position. This arrangement permits the plate A to be moved into any longitudinal position and automatically remains in that position without manipulating any other means.

70 When it is desired to move the plate A 80 downward, the end 25 of the lever 23 is pressed downwardly whereupon the brake mechanism is released by moving the roller 21 out of engagement with the contacting members and the shaft C, and consequently 75 the plate A, can be moved in either direction. Upon release of the end 25, the roller 21 automatically drops into braking position.

When it is desired to move the plate A 85 downwardly to any desired position, it is 90 only necessary to press the end 25 downwardly and hold it down until the plate A reaches the desired position; whereupon the end 25 is released and the roller 21 then 95 automatically drops into braking position and automatically locks the plate A in the adjusted position.

100 The brake mechanism automatically locks the plate A against downward movement in any position to which it may be moved and automatically permits the upward movement of the plate A as well as manual manipulation so that the plate A can be moved up or down or to permit the plate A to move downwardly due to the gravity thereof to 105 any desired position.

110 The mechanism to rotate the shaft C in the direction opposite to that of the arrow shown in Fig. 4 is associated with and acts on the cup or drum 15 as does the brake 115 mechanism.

The bracket 26 has the lower end 27 thereof secured to the base D and the other end 28 thereof extends into the drum 15 to form an abutment for the roller 29. The bumper 30, of non-metallic material, is fixed in the end 28 and normally abuts the bottom of the roller 29.

120 The block 31 is secured to the inside of the cover 17 in proper relation to the end 28 of the bracket 26. The block 31 is notched to form the wall 32 and is disposed so that this wall 32 is angular to or eccentric with the inner wall 33 of the flange 16 and so that the space between the lower end of the wall 125 32 and the wall 33 is less than the space between the upper end of the wall 32 and the wall 33. The bumper 34, of non-metallic material, is fixed into the wall 35 of the block 31.

The roller 29 lays loosely in the space between the walls 32 and 33 and normally rests against the bumper 29.

The lever E is fulcrumed on the base D 5 and has the slot 36 through the inner end 37 thereof.

The pin 38 is secured to the cover 17 and extends outwardly therefrom and through the slot 36.

12 When the outer end 39 of the lever E is pushed downwardly, the end 37 thereof moves upwardly. In this upward movement of the end 37, the pin 38 is also moved upwardly and, since the pin 38 is secured to 15 the cover 17 and the cover 17 can rotate on the shaft C and the block 31 is also secured to the cover 17, the upward movement of the pin rotates the cover 17 in the direction opposite to that of the arrow in Fig. 4. In 20 this rotative movement of the cover 17, the block 31 moves with it and, since the walls 32 and 33 are eccentric and the roller 30 lies loosely or floatingly between these walls, the wall 32 wedges the roller 30 against the wall 25 33 and thereby grips the wall and the cup or drum 15 and rotates the same with the cover. Since the drum is unrotatable on the shaft C, the movement on the cover and consequent movement of the drum also moves 30 the shaft and the mechanism operatively connected therewith and consequently moves the plate A.

With this operating mechanism, the shaft C can be rotated in either direction by manually rotating the drum when the brake is 35 released and can be rotated in a direction opposite to that shown by the arrow in Fig. 4 by means of the lever E.

The operation of the entire mechanism 40 shown and described is as follows:—

When the members are in position shown in the drawing, the plate A is moved upwardly by depressing the end 39 of the lever E as described and such upward movement 45 is periodical or in steps and the length of each step may be adjusted by the screw 40.

When the outer end 25 of the lever 23 is depressed, the brake is released and the plate A moves downward automatically, due 50 to gravity in the present instance, and this downward movement of the plate is arrested by releasing the end 25 of the lever 23 as previously described.

Therefore, the plate A can be adjusted 55 primarily to any desired up or down position by releasing the brake and rotating the shaft C manually; the plate A can be permitted to move downwardly to any desired position by operating the lever 23 to release 60 the brake until the plate has attained the desired downward position and then letting the brake act normally to lock the plate in the desired position; the plate can be moved upwardly by operating the lever E; the operation of each of the levers is completely 65

independent of the operation of the other lever; the operation of either one of the levers does not affect the operation of the mechanism operated by the other lever; each of the mechanisms connected with the levers 70 operates automatically in co-operation with the mechanism connected with the other lever; and the plate can be adjusted to desired position, in either direction, or can be moved periodically to spaced positions in 75 one direction, and can automatically be held in any position, and can be moved from this position without operating the brake mechanism.

I claim:—

1. In an apparatus of the character described, a rotatable member normally free to be rotated, clutch means associated with said rotatable member and normally out of engagement therewith, and an operating 80 means arranged to throw said clutch means into engagement with said rotatable member during the initial portion of the operating movement of said operating means and to rotate said rotatable member during a 85 subsequent portion of the same operating movement of said operating means.

2. In an apparatus of the character described, a rotatable member normally free to be rotated in one direction, a brake including clutch means normally locking said member against rotation in the opposite direction, and means to release said clutch means to permit the rotation of said member in either direction.

3. In an apparatus of the character described, a rotatable member normally free to be rotated in one direction, a brake including clutch means normally locking said member against rotation in the opposite direction, means to release said clutch means to permit the rotation of said member in either direction, and operating means including clutch means to engage said member to rotate the same in said one direction when 100 this operating means is operated.

4. In an apparatus of the character described, a shaft individually rotatable, and a roller normally contacting said shaft and a wall arranged at an angle to the circumference of said shaft to normally lock said member against rotation in one direction.

5. In an apparatus of the character described, a rotatable member, a housing having a wall arranged at an angle to the circumference of said member, and a roller in said housing and normally contacting said member and said wall to normally lock said member against rotation in one direction.

6. In an apparatus of the character described, a rotatable member, a roller normally contacting said member and a wall arranged at an angle to the circumference of said member to normally lock said member against rotation in one direction, and a lever 125

operable to move said roller out of engagement with said member and said wall to permit the rotation of said member in either direction.

5 7. In an apparatus of the character described, a rotatable member, a roller normally contacting said member and a wall arranged at an angle to the circumference of said member to normally lock said member against rotation in one direction, operating means including clutch means to engage said member to rotate the same in the opposite direction when the operating means is operated, and means for moving said roller out of the locking position thereof to permit the rotation of said member in either direction.

20 8. In an apparatus of the character described, a rotatable member, a roller normally contacting said member and a wall at an angle to the circumference of said member to normally lock said member against rotation in one direction, a roller normally held out of contact with said member and 25 with a wall arranged at an angle to the circumference of said member, a lever operable to move the first mentioned roller out of locking position thereof to permit the rotation of said member in either direction, and 30 a lever arranged to move the second mentioned roller into contact with said member and with the second mentioned wall and to rotate said member in the opposite direction.

35 9. In an apparatus of the character described, a rotatable member having a cup, a roller acting on the outside of said cup to lock said member against rotation in one direction, and a roller acting on the inside of 40 said cup to rotate said member in the opposite direction.

45 10. In an apparatus of the character described, a rotatable member having a cup, a roller normally acting on the outside of said cup to lock said member against rotation in one direction, a roller inside of said cup and normally out of contact with said cup, means for moving the first mentioned roller out of engagement with the outside of 50 said cup to permit the rotation of said member in either direction, and means for moving the second mentioned roller into contact with the inside of said cup and rotating said member in the opposite direction.

55 11. An apparatus of the character described, including, a rotatable member, a drum secured to said member and rotatable therewith, a cover journaled on said member adjacent to said drum, a block secured 60 to said cover and extending into said drum and having an abutment wall eccentric with the wall of said drum, a roller loosely confined between the eccentric wall of said block and the inside of the wall of said drum, an abutment normally retaining said

roller out of engagement with both of said walls to permit the rotation of said drum in either direction, and means for rotating said cover and thereby wedging said roller between both of said walls and rotating said drum with said cover.

70 12. An apparatus of the character described, including, a rotatable member, a drum secured to said member and rotatable therewith, means for rotating said drum in one direction, a housing adjacent to said drum and having an abutment wall eccentric with the wall of said drum, a roller loosely confined in said housing and normally contacting both of said walls to lock 75 said drum against rotation in the opposite direction, means for releasing said roller to permit the rotation of said drum in either direction, and said roller adapted to automatically disengage said walls when said 80 means for operating the drum is in operation.

85 13. An apparatus of the character described, including, a rotatable member, a drum rotatable with said member, a cover 90 journaled on said member adjacent to said drum, a block secured to said cover and extending into said drum and having an abutment wall eccentric with the wall of said drum, a roller loosely confined between the eccentric wall of said block and the inside of the wall of said drum, an abutment normally retaining said roller out of engagement with both of said walls to permit the 95 rotation of said drum in either direction, means for rotating said cover and thereby wedging said roller between said walls and rotating said drum with said cover, a housing adjacent to said drum and having an abutment wall eccentric with the wall of said drum, a roller loosely confined in said 100 housing and normally contacting both of said walls to lock said drum against rotation in the opposite direction, means for releasing the secondly mentioned roller to 105 permit the rotation of said drum in either direction, and the secondly mentioned roller adapted to automatically disengage said walls when said means for rotating the drum is in operation.

110 14. An apparatus of the character described, including, a plate movable in two opposite directions, a rotatable shaft, operative connection between said plate and said shaft to move said plate upon rotation of said shaft, means for rotating said shaft in one direction to move said plate in one direction, a brake acting on said shaft to prevent the rotation thereof in the opposite direction to lock said plate against movement in the opposite direction, and means for releasing said brake to permit the movement of said plate in either direction.

115 15. An apparatus of the character described, including, a plate movable in two 120

- opposite directions, a rotatable shaft, operative connection between said plate and said shaft to move said plate upon rotation of said shaft, means for rotating said shaft in 5 one direction to move said plate in one direction, a brake acting on said shaft to prevent the rotation thereof in the opposite direction to lock said plate against movement in the opposite direction, said brake automatically 10 disengaging from said shaft when said means for rotating the shaft is in operation, means for releasing said brake to permit the movement of said plate in either direction, and said means for rotating the 15 shaft and said means for releasing the brake operable independently of each other and the operation of neither one of these means depending upon the operation of the other of these means.
- 20 16. An apparatus of the character described, including, a plate movable in two opposite directions, a rotatable shaft, operative connection between said plate and said shaft to move said plate upon rotation of 25 said shaft, means for rotating said shaft in one direction to move said plate in one direction, a brake acting on said shaft to prevent the rotation thereof in the opposite direction to lock said plate in the opposite direction against the weight thereof, said 30 brake automatically disengaging said shaft when said means for rotating the shaft is in operation, means for releasing said brake to
- 35 permit the movement of said plate in either direction, and said means for rotating the shaft and said means for releasing the brake operable independently of each other and the operation of neither of these means depending upon the operation of the other of these means.
- 40 17. In a copy holder, a movable plate, a rotatable shaft, connecting means between said plate and said shaft, and means automatically locking said shaft against rotation in one direction and in any position and thereby lock said plate against movement in one direction and in any position into which the same is moved.
- 45 18. In a copy holder, a movable plate, a rotatable shaft, connecting means between said plate and said shaft, means automatically locking said shaft against rotation in one direction and in any rotative position thereof and thereby lock said plate against movement in one direction and in any position into which the same is moved, means 50 for rotating said shaft in the opposite direction and normally held out of engagement with said shaft, and means automatically engaging said shaft to rotate the same in the opposite direction when said rotating means is operated and thereby move said plate in the opposite direction.
- 55 In testimony of the foregoing, I affix my signature.
- 60 PETER GRABLER.
